UNITED STATES PATENT OFFICE.

SAMUEL J. SPURGEON, OF HOUSTONIA, MISSOURI.

PAPER AND ENVELOPE PACKAGE.

SPECIFICATION forming part of Letters Patent No. 279,283, dated June 12, 1883.

Application filed August 14, 1882. (Model.)

To all whom it may concern:

Be it known that I, SAMUEL J. SPURGEON, of Houstonia, in the county of Pettis and State of Missouri, have invented a new and Improved Paper and Envelope Package, of which the following is a full, clear, and exact description.

Reference is to be had to the accompanying drawings, forming part of this specification, in which similar letters of reference indicate corresponding parts in all the figures.

Figure 1 is a longitudinal view of my improved combined paper and envelope package, showing it opened ready for writing. Fig. 15 2 is a longitudinal view of the same, showing it closed. Fig. 3 is a perspective view of the same, showing it partly opened.

A series of sheets, A, of writing or note paper, which may be ruled, if desired, are united 20 at one corner by an eyelet, B, or any other suitable analogous device, by means of which eyelet the covering-sheet C is held on the package. This covering-sheet is of the size of the sheets A, with an additional flap, D, having one edge cut diagonally. The width of 25 the flap D at the widest end may be equal to the width of the sheets A, or may be slightly greater or less, as may be desired. The flap D is gummed along the diagonal edge on the 30 inner surface, and, if desired, the entire outer corner, E, may be gummed. The writer writes on the sheets A, and then folds them over the eyelet B in the manner that the covering-

sheet C is folded over the eyelet in Fig. 1. The writer may write on one or both sides of the 35 sheet, as may be desired. The covering-sheet C is preferably creased at the base of the flap D, as shown at a in Fig. 1. The covering-sheet C is folded over the uppermost sheet A, the gummed edge and corner of the flap are 40 moistened, and the flap D is folded over the lowest sheet A, to which it adheres, and the corner E is folded over the uppermost sheet A, to which it also adheres, thereby holding the 45 package closed. The stamp can be gummed on the corner E or on the edge of the same as a further security. More or less sheets A can be contained in the package.

The above-described combined envelope and paper package is very convenient, especially 50 for travelers. It also affords very great conveniences in filling the letters.

If desired, the covering-sheet can be made of thicker paper than the rest of the sheets.

Having thus fully described my invention, I 55 claim as new and desire to secure by Letters Patent—

An envelope formed of a sheet, C, extended from fold a on one side to form the flap D E, in combination with two or more paper sheets, 60 A, eyeleted to one corner of sheet C, whereby said paper may be enveloped, as described.

SAMUEL J. SPURGEON.
